UNITED STATES PATENT OFFICE.

HENRY HUNT, OF GREENVILLE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 12,824, dated March 21, 1882.

Application filed February 11, 1882. Term of patent 3½ years.

To all whom it may concern:

Be it known that I, HENRY HUNT, of Greenville, in the county of Hudson and State of New Jersey, have invented a new and original 5 Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

The field *a*, which is ornamented by small 15 fillet-work, bears various flower and other figures on small connecting stems that traverse the field irregularly.

A is an irregular flower with a leaf spray above it.

B is a group with a central horizontal bar, pointed leaves to the right, small flowers below, a scalloped flower at the base, and a split branch and bud form above.

C is a group consisting of an ornamented 25 rectangular figure partially concealed by flowers and leaves below and to the left, with a leaf-spray on the right.

D is a group of small star-shaped flowers with two upwardly-projecting blossom sprays.

b is a small circular flower with surrounding leaves.

E is a group with an open flower below and small pointed leaves and an irregular stem above.

F is a fan-like figure with a circular projection on the right.

c is a conical leaf figure, and *d* a small circular flower with pointed leaves.

G is a conical flower figure pointed downward and to the right, with three large leaves as a base and a projecting bud.

On a flowering stem from *G* projects a conical flower with tufted top, forming the cluster *H*.

K is a figure resembling two hearts, with leaf forms above and below.

L is an open flower with pointed petals.

M is a circular flower with pointed petals on each side.

N is a cluster of two circular flowers and 50 buds with a bud spray and petals below.

e is a small conical flower with tufted crown.

From *L* projects a forking stem, bearing on the left fork the group *O*, which consists of a small radiating flower with pointed leaves and two projecting bud sprays, and on the right fork the group *P*, consisting of one flower with pointed petals and a circular flower to the left.

On a stem from *P* is the group *Q*—a conical flower and leaves with vertical bar.

R is a group not connected with any of the surrounding figures, consisting of a double-centered circular flower with pointed petals above, a small flower below, and a flower with indented edge on the left.

S is a group consisting of a small fan-like figure, a pendent conical figure, a small circular flower, and above a rectangular figure with indented edge on the left and ornamented with conical figures at its lower part. *T* is a group 70 consisting of an open flower with projecting leaves and a bud spray. These two groups *S* and *T* take the place in the general grouping of figures shown on the left of the photograph occupied by the groups *O* and *Q* in the 75 otherwise identical grouping of figures on the right of the photograph.

I claim—

1. The design for carpets, consisting of the figures *A B C D E F G H K L M N O P Q R S T b c d e*, with connecting-stems, substantially as shown.

2. The design for carpets, consisting of the figures *A B C D E F G H K L M N O P Q R S T b c d e*, with connecting-stems, and ground 85 *a*, substantially as shown.

HENRY HUNT.
